Pierre James BY ATTORNEY

UNITED STATES PATENT OFFICE.

FRANK F. SINKS, OF SEATTLE, WASHINGTON.

SHORE.

Application filed October 20, 1924. Serial No. 744,641.

To all whom it may concern:

Be it known that I, FRANK F. SINKS, a citizen of the United States, residing at Seattle, in the county of King and State of

5 Washington, have invented certain new and useful Improvements in Shores, of which the following is a specification.

This invention relates to shores designed, more especially, for use in supporting concrete receiving molds or forms in the construction of reinforced concrete floors.

The object of the invention is the provision of a shore having extensible characteristics, which is of strong and durable construction, convenient to use, and readily adjustable to selected lengths.

More specific objects and advantages of the invention will appear in the following specification.

20 The invention consists in the novel construction, adaptation and combination of parts, a detailed description of the preferred embodiment of the same will be hereinafter given in connection with the accompanying drawing, in which,—

Figure 1 is a front elevational view showing a shore embodying my invention applied in connection with a beam portion of a concrete floor. Fig. 2 is a side elevation applied 30 in connection with a floor slab-portion. Fig. 3 is a detail vertical section to an enlarged scale taken substantially on line 3—3 of Fig. 2. Fig. 4 is a horizontal section on line 4—4 of Fig. 3. Fig. 5 is a vertical section on line 5—5 of Fig. 4.

A concrete floor construction is usually formed with beams, such as 10 in Fig. 1, and slab elements, such as 11 in Fig. 2, from plastic concrete and suitable reinforcing devices, not shown, within suitable molds as indicated by 12 and 13.

Hitherto, such molds have been supported by wooden props cut to lengths somewhat less than the height of the molds above a support as the floor 14 next below.

A block or piece of timber, such as 15 or 16, is desirably placed upon the upper end of the prop to afford a relatively large bearing against the mold and, finally, wedge

blocks are forced under the lower end of the prop to elevate the latter into position to support the mold.

My invention overcomes objections to the shoring means above referred to by providing a shore extensible in itself adapting it to be used time after time, and eliminating waste of material and lessening the expense of labor in applying.

According to the present invention, a shore comprises two members 17 and 18, preferably of wood, which are slidably connected together for relative telescopic movement.

The lower member 17, or standard, consists of a single piece adapted to slidably fit between longitudinal parallel spaced companion pieces 18¹ and 18² of the upper member 18, or extension, as it will be hereinafter termed.

The longitudinal pieces 18¹ and 18² are held in their spaced relations by being rigidly secured adjacent their upper ends to interposed blocks 20 and 21, and adjacent their lower ends by means of plates 22 secured to the front and rear surfaces of said pieces and by reinforcing straps 23. Provided in said extension pieces 18¹ and 18² at opposite sides of the channel 19 are pairs of axially aligned sockets 24, said pairs of sockets being spaced apart longitudinally of the extension as, for example, five or six inches center to center.

Mounted upon the upper end of the standard 17 and secured thereto as by means of screws 25 is a metal cap 26 having a centrally disposed aperture which is tapped to receive the screw threads of a vertically disposed jack screw 27 whose lower end is accommodated by a cavity 28 provided in the standard 17. Above its screw threaded portion, said jack screw is provided with a wrench-engageable polygonal portion 29 and thereabove the jack screw is provided with a cylindrical end 30 which extends into a recess provided in the under side of a metal body 31, hereinafter designated as the carrier.

32 represents a screw threaded bolt having a head positioned, as shown in Fig. 3,

in a recess 33 of the carrier and extending therefrom axially of the jack screw to connect the latter to the carrier against separation.

- 5 The connection above explained of the carrier to the jack screw permits the latter to be rotated to effect the raising and the lowering of the carrier with respect to said standard.
- 10 The carrier is provided with lugs 34 arranged as best shown in Fig. 4 to serve as guides with respect to the extension side pieces 18¹ and 18², and cooperate with the plates 22, which also serve as guides, for 15 maintaining the extension 18 in axial alignment with the standard 17.

Said carrier is provided with a transversely arranged bore 35 for the reception of complementary coupling pins 36 which 20 are engageable in a selected pair of sockets 24 to unite the carrier 31 to the extension 18 for conjoint longitudinal movement with relation to the standard 17 when the jack screw is rotated.

- 25 The pins 36 are moved into engaging relation with the extension sockets 24 or retracted therefrom by suitable controlling means, said means as illustrated consisting of wire attachments 37 extending radially 30 of the respective pins through slots 38 of the carrier into positions to be conveniently manipulated by the operator.

The outer end of each slot 38 terminates advantageously in a laterally disposed portion 39 (Fig. 4) into which the wires 37 are brought when it is desired to secure the pins against accidental disengagement with the extension member.

- For use, a shore is first regulated to a 40 length approximating but shorter than requisite for a specific application, such regulation being accomplished by the operator slidably moving the extension 18 until suitably located sockets 24 are brought into 45 position to register with the carrier pins 36 which are thereupon protruded to engage within such sockets. This primary regulation is best effected when the shore is in a substantially vertical position.

- 50 After being thus regulated the jack screw 27 is rotated by means of a suitable wrench or instrument (not shown) to act through the medium of the carrier to cause the extension to be elevated into engaging relation with the work.

In practice cleats or stays, such as indicated by dotted lines 40 and 41 in Figs. 1 and 2, are desirably nailed to a shore and also to the mold bearing timbers 15 and 16 60 above mentioned to obviate any accidental dislodgment of the shore.

As changes may be made in the above described specific embodiment, within the scope of the appended claims, without departing 65 from the spirit thereof, it is intended that

the matter contained in the specification and drawing shall be considered as illustrative only of the preferred construction.

What I claim, is,—

1. A shore of the character described 70 having in combination a standard, an extension having a channel therein to receive said standard for relative longitudinal movement, a cap secured upon an end of said standard, said cap being provided with a screw threaded aperture, a screw engaging in the threads of said cap aperture, a carrier mounted upon said screw, and means provided upon said carrier and engageable in said extension for coupling the latter with 75 said extension.

2. A shore of the character described having in combination, a standard, a screw operatively connected to an end thereof, an extension having a channel therein to receive the standard for relative sliding movement, said extension being provided at opposite sides of its channel with longitudinally spaced sockets, a carrier mounted upon 80 an end of said screw, and retractile devices 85 provided in the carrier and engageable in said sockets selectively for coupling the carrier with said extension.

3. In a shore of the character described, 90 a standard, an extension connected to the standard for relative longitudinal movement, said extension being provided with longitudinally spaced pairs of sockets, a carrier slidably connected to said extension, means carried by said carrier for coupling 95 the latter to said extension at predetermined positions longitudinally thereof, and screw devices operatively connected to the standard and to the carrier for effecting longitudinal adjustments to the extension with 100 respect to the standard.

4. A shore of the character described, 105 comprising a standard, a cap secured thereto, said cap being provided with a screw threaded aperture, an extension having a 110 channel to receive said standard for relative longitudinal movement, pairs of complementary sockets provided in the extension at opposite sides of its channel, said pairs of 115 sockets being disposed in spaced relation longitudinally of the extension, a screw engaging the threads of the cap aperture, a carrier mounted upon the screw and having a 120 slidable connection with the extension, and laterally movable pins provided in the carrier and engageable with the pairs of sockets selectively for coupling the carrier to said extension at a predetermined elevation.

5. In a shore, the combination of a standard, 125 an extension comprising a pair of spaced relatively fixed members, whereby a channel is formed between the members, in which channel the standard is slidably received, the members having opposed spaced sockets, the standard having a threaded bore 130

in its end received between the members, a screw engaging in the bore in the standard, a carrier revolvably mounted on the screw, the carrier having a transverse bore, and a 5 pair of pins in the bore arranged for selective engagement in opposed sockets in the spaced members.

6. In a shore, the combination of a pair of members fixed to one another in spaced 10 relation, a standard slidably between the members, the standard having a bore at its

end received between the members, a screw engaging in the bore in the standard and adjustable lengthwise of the standard, a carrier mounted on the screw, and pins carried by the carrier for projection laterally from the carrier, the members having pairs of opposed sockets for receiving the pins. 15

Signed at Seattle, Washington, this 16th day of September, 1924.

FRANK F. SINKS.
